NOEL DEISCH, OF WASHINGTON, DISTRICT OF COLUMBIA.

PAGE-END-MARGIN INDICATOR.

Application filed December 21, 1925. Serial No. 76,768.

The present invention relates to typewriters, and particularly to page end indicators therefor, for the purpose of indicating or announcing the approach of the end of the 5 page in order that the desired margin at the foot thereof may be provided for, without resorting to the necessity of rotating the platen backwardly to examine how near the typewriting has approached the end of the 10 page.

It is one object of the invention to provide such a page end indicator for typewriters which is adjustable for various widths of bottom margins and which indicates accurately 15 the moment when the typewriting should be stopped in order to leave the desired margin.

A further object of the invention is the provision of such a device which embodies 20 means whereby it is automatically actuated.

A still further object of the invention is to provide a page end indicator which is so arranged that it will not cause any injury to the paper being written upon and which permits of the free and unobstructed insertion 25 of the paper preliminary to typewriting thereon.

It is found in practice that many page end indicators are commercially impracticable 30 for various reasons, such as not being adjustable for various widths of page end margins, or because they require to be set each time a sheet of paper is inserted in the machine, or because they cause scoring or other damage 35 to the paper by reason of the fact that they exert too much pressure on the sheet, or because they are too complicated in construction to be commercially usable. It is a still further object of the present invention to ob- 40 viate the above enumerated and other diffi- culties heretofore encountered and to pro- vide a device of the class described which will be relatively simple in construction, reliable in operation, and which will not cause 45 marking, scoring or other defacing of the paper.

Still other objects and advantages of the invention will appear from the following description taken in connection with the accompanying 50 drawings, which illustrate a preferred embodiment thereof, but which

are not to be taken as a definition of the limits of the invention, reference being had to the appended claims for that purpose.

In the drawings:

Fig. 1 is a side elevation of one preferred embodiment of the invention showing the page end indicator lever set in one position, and the striker hammer for the announcing or indicating bell set in position to strike;

Fig. 2 is a similar view partly broken away and showing the parts in another position, the striker hammer being in the position which it occupies after being released, and the indicator setting lever being changed from one position to another;

Fig. 3 is a front elevation of the mechanism shown in Fig. 2 and also illustrating one end of the platen, the margin indicating or setting lever being shown in its vertical 70 position;

Fig. 4 is an enlarged axial perspective view of the release assembly;

Fig. 5 is a diagrammatic side elevation of the release assembly and illustrating the action of forces therein;

Fig. 6 is a side elevation of the margin indicating or setting lever and the release assembly;

Fig. 7 is a side elevation of one preferred embodiment of an automatic setting device for setting the ratchet member carrying the striking hammer;

Fig. 8 is a side elevation showing another preferred embodiment of automatic means for setting the ratchet member and particularly illustrating the first of three successive phases in its action;

Fig. 9 is a similar view of the parts shown in Fig. 8 and illustrating the position of the parts in the second phase of their action in setting the ratchet member;

Fig. 10 is a similar view of the same parts showing their position in the third phase of their action;

Fig. 11 is a side elevation of one face of a cam member associated with the automatic ratchet setting mechanism of Figs. 8, 9, and 10;

Fig. 12 is a front elevation illustrating the cam member of Fig. 11 and showing its position on the end of the platen.

Referring in detail to the drawings and particularly to Figs. 1 to 6 inclusive, a fixed bell 9 is arranged to be struck by a hammer or striker 10 carried at the end of a rod 11 fixed to the ratchet member 12. The ratchet member 12 is rotatably mounted by means of the sleeve 17 on the platen end plate sleeve 18 on the platen shaft 13 and is provided with the arcuate ratchet 14 around part of its periphery and with the actuating lever arm 15 having at its end a flat portion 16 by which it may be depressed. The ratchet member 12 is constantly urged in the direction of the arrow A, Fig. 1, by means of a spring 19 which has one of its ends fixed in the carriage frame 1 and its other end fixed in the ratchet member 12. It will be evident from Fig. 1 that the ratchet 12 is pressed downwardly by means of the flat portion 16 for the purpose of moving the striker or hammer 10 in position to strike the bell 9 at the proper moment.

Means are provided by the invention for maintaining the ratchet 12 in the set position until the desired moment and then automatically releasing it to cause the striker 10 to strike the bell 9, including mechanism for variably positioning said means to cause the announcing device to be actuated when the writing has approached as far toward the page end as desired, the page end indicating mechanism being capable of being set to indicate margins of different widths.

Referring in detail to the preferred form of striker release mechanism herein embodied, a lever 22 (see Figs. 6, 1, 2, 3 and 4) is provided intermediate its ends with an elongated slot 23 by which it is mounted upon the platen shaft 13 which passes through said slot. At its upper end the lever is provided with a flat portion 24 by which it may be depressed and rotated about the platen shaft 13. Fixed to the lever 22 is a stud 25 extending laterally therefrom, the purpose of which will presently appear. Adjacent one face of the lever 22 and mounted for relative rotation with respect to the platen shaft 13 is a collar 26 which has affixed thereto one end of a coil spring 27 which has its other end 28 fixed to the lever 22, the effect of the spring 27 being to urge the lever 22 upwardly so that the platen shaft 13 will normally be located at the bottom of the slot 23.

A sector 33 is fixed to the carriage frame 1 by means such as screws 34 and is provided on its inner periphery with a series of notches 35 which are preferably indicated by numbers on the face of the sector, as shown in Figs. 1 and 2. The pin 25 on the lever 22 is normally located in one of the slots 35 and may be moved from one notch to another by pressing downwardly on the flat portion 24 of lever 22 for the purpose of disengaging

the pin 25 from the notch in which it may be located, and then rotating the lever 22 in either direction about the platen shaft 13 until the pin 25 is brought opposite to the desired notch, whereupon the flat portion 24 of lever 22 is released, and the pin 25 is then caused automatically to move into the selected notch by means of the coil spring 27.

Carried preferably at one end of the lever 22 is a striker release mechanism (see particularly Fig. 4). This mechanism, in the present preferred form of the invention, includes a member adapted at certain times to bear on and be controlled by a page inserted in the machine, this member being shown and hereinafter referred to as a pivoted detent arm 42, which at one phase of its operation bears on the paper 43 and which in another phase of its operation is adapted to enter the annular groove 44 located at the end of the platen 45, as shown in Fig. 3.

The detent 42 is formed with a sleeve 46 by means of which it is mounted on the arbor 47 which is fixed in and projects laterally from the lower end of the lever 22. The sleeve 46 has formed thereon and projecting therefrom in a direction opposite to the detent 42, an arm 48 in which is fixed a pin 49 projecting laterally therefrom toward the lever 22 and extending under a lug 50 formed on said lever. Rotatably mounted on the pin 49 is a pawl 53, to the lower end of which is fixed a laterally projecting pin 54 which extends beneath the arm 48 and serves as an abutment stop for limiting the upward and rotary movement of the pawl 53 on the pin 49 by engaging with the bottom of the arm 48. A coil spring 56 surrounds the arbor 47 and has one of its ends fixed to said arbor nearest the lever 22 and has its other end fixed in or to the pawl 53, and is coiled under tension so that it tends normally to raise the pawl 53 and also to raise the arm 48 through the pin 54 which is fixed to the lower part of the pawl 53 and abuts against the bottom of the arm 48. It will be obvious that as the detent 42 is located on the opposite side of the sleeve 46 from the arm 48, the tendency of the spring 56 is normally to lower said detent 42.

Means are provided by the invention for holding the detent 42 out of the annular groove 44 during the insertion of the paper 43 in the machine for the purpose of preventing any tearing or scoring of the paper which might otherwise occur; and for causing the detent 42 to bear upon the paper 43 after it has been inserted, so that when the end of the paper 43 passes by the detent 42, said detent will be urged by the mechanism hereinbefore and hereinafter described, into the groove 44 for the purpose of releasing the signaling device to warn the operator that the typewriting has approached the

bottom of the page to the point where exactly the desired margin is left, so that the paper can be removed from the machine and a new sheet inserted. When in its normal 5 position the detent 42 is held a slight distance away from the platen 45 by the spring 56, so that the paper in entering the machine does not come into contact with the detent 42 and does not have to lift any kind of 10 lever. This is an important feature of the invention, since indenting or tearing of the edge of the paper is thereby avoided. No pressure is exerted on the paper until the detent 42 is made to descend on the paper 15 through springing back or setting the ratchet member.

Certain mechanism is associated with the lever 22 and parts carried thereby, which, when released, causes the signal to be operated, and in the present embodiment of the 20 invention this mechanism includes the ratchet member 12 hereinbefore described carrying the striker hammer and normally urged (as viewed in Figs. 1 and 2) in a 25 counterclockwise direction by the spring 19. The ratchet member 12 is pivoted by means of the sleeve 17 on the platen end plate sleeve 18 on the platen shaft 13 adjacent the lever 22 and so arranged that the pawl 53 is 30 adapted to engage the ratchet teeth 14, as shown in Fig. 1.

It will be noted that the device thus far described is set manually, that is, the striker mechanism is set for each page inserted 35 in the machine by depressing the arm 15 of the ratchet member 12 by means of the flat portion 16 on the end thereof. The operation of this mechanism may be briefly described as follows:

40 The operator having determined the amount of page end margin it is desired to leave on any sheet or group of sheets, depresses the lever 22 and rotates it in either direction until the pin 25 is brought opposite and under the desired notch 35 to cause 45 the signal to be operated at the proper moment. The signal may be set to indicate when a relatively small page end margin has been left by setting the lever opposite 50 one of the lower numbered notches on the arcuate sector 33, as it appears in Figs. 1 and 2; and a larger or deeper page end margin may be 55 provided for by setting the pin 25 in one of the notches toward the left-hand side of said arcuate sector 33, as it appears in Figs. 1 and 2. By setting the lever 22 in the desired position, the parts shown in Fig. 4 carried 60 at the bottom of said lever are thus brought to a predetermined position and are there maintained until this position is again changed at the will of the operator. The handle 16 on lever 15 is then depressed, 65 causing the ratchet member to rotate in a

clockwise direction (as these parts appear in the drawing), thus causing one or more of the ratchet teeth 14 to ride over the pawl 53, which falls behind one of the ratchet teeth, as shown in Fig. 1, and holds the ratchet in 70 position as long as the paper 43 holds the detent 42 out of the annular groove 44 in the end of the platen. When the end of the paper 43 passes beyond the detent 42, said 75 detent, urged by the spring pressed ratchet member 12, falls into the groove 44, describing a rotary motion about the arbor 47, and as the parts appear in the drawing, moving upwardly and in a clockwise direction. The arm 48, which is also fixed to the sleeve 80 46, at the same time moves downwardly in a clockwise direction and carries downwardly with it the pawl 53, which, as soon as it clears the ratchet teeth with which it is engaged, releases the ratchet member 12, permitting said ratchet member to rotate in a 85 counterclockwise direction under the action of spring 19 and causing the hammer 10 to strike the bell 9 and thus indicate to the operator that the typewriting has approached just near enough toward the bottom of the page to leave the desired margin.

It will be obvious that the detent 42 will not enter the groove 44 as long as it is prevented from doing so by the paper 43, and referring to Fig. 5 of the drawings and to the following detailed explanation, it will likewise be obvious that the spring pressure on the ratchet 12 causes the pawl 53 to be released from said ratchet the moment the 100 paper 43 has moved far enough to permit the detent 42 to enter the annular groove 44 in the end of the platen. If the arrow F represents the direction of the resultant of the force of the ratchet tooth acting on the pawl 53, than a force *oa* will be exerted on the pawl 53, causing it to maintain its position with respect to arm 48, and a force *ob* will be exerted tending to turn the assembly 105 42, 48, 53, so as to cause the detent 42 to exert a pressure on the paper. Normally (i. e., when there is no paper in the machine and the striker is released) the detent and pawl assembly is maintained in the position shown in Fig. 4 through the action of the spring 110 56. The pressure exerted on the paper by the detent can obviously be made of any desired minimum value by determining the ratio of the turning moment of the striker spring 19 to the release spring 56, as also 115 by determining the distance *ob*.

The initial downward movement of the lever 22, when it is being set for a predetermined margin, also carries the pawl 53 out of engagement with the ratchet, allowing its 120 movement to any new position on the ratchet. From this it is plain that the device can be set for a new width of margin irrespective of whether there be paper on the platen or not, or whether the ratchet member has been 125 130

previously set or not. The width of margin at the page end is of course controlled by the circumferential distance of the outer end of the detent 42 from the type imprinting line.

In the form of setting mechanism above described, the striker mechanism is sprung back or set by hand. The invention also contemplates and includes automatic methods and means for performing this function, which will now be described. In one form of automatic means for this purpose, shown in Fig. 7, a lever 63 is rotatably mounted on a fixed pivot 64 secured to the machine frame, and the lever 63 carries at its other end a roller 65 adapted to bear upon the platen 45, this construction specifically forming no part of the present invention, but being a device applied as part of the standard equipment of some machines for the purpose of maintaining the paper closely pressed on the platen. In inserting a sheet of paper in the machine, the lever 63 must be drawn back manually by pressing on the end 66 of a lever 67 fixed to and projecting from the pivoted arm or lever 63. In accordance with the present invention, means are provided for utilizing this action for the purpose of effecting the setting of the ratchet member 12 hereinabove described. For this purpose, a connection is provided between the pivoted lever 63 and the ratchet 12, said connection including an arm 69 pivotally mounted at one of its ends at 70 to the pivoted lever 63 and provided with a pin 72 at its other end which enters an arcuate slot 73 provided in the ratchet member 12. On drawing back the lever 63 for the purpose of inserting paper in the machine, the arm 69 is drawn back also and carries with it by means of the pin 72, the ratchet member 12, whereupon one or more of the ratchet teeth ride over the pawl 53 which engages one of the ratchet teeth and holds the ratchet in the set position as hereinbefore described. When the lever 63 is released, it returns to its original position with the roller 65 bearing on the platen 45, and during this return movement the pin 72 rides forwardly in the slot 73 provided in the ratchet 12 without, however, moving the ratchet, which is held by the pawl 53, the pin 72 merely moving to a position at the other end of the slot. When the ratchet 12 is released by the mechanism hereinabove described, the ratchet 12 rotates partially on the platen shaft 13 carrying with it the striker hammer and operating the signal, and during this motion the pin 72 remains stationary while the ratchet 12 with its slot 73 rotates, thus causing the pin 72 at the end of this rotary motion to lie in the left-hand end of the slot as shown in Fig. 7. It will be seen that the setting of the striking mechanism is thus automatically accomplished in one of

the already necessary actions of operating the machine, and without any further attention or thought whatever on the part of the operator.

The invention also contemplates and includes a further automatic setting arrangement for the ratchet 12, and in a preferred form thereof this setting is accomplished through a cam and lever action in the process of turning or rotating the platen when a sheet of paper is being inserted in the machine. This form of the invention is illustrated in Figs. 8 to 12 inclusive.

As shown, a cam 84 is provided with a cam surface 85 and is attached by screws to, or may be integral with, the end of the platen 45. A stud 87 rides on the cam surface 85 and is fixed in the free end of a lever 88 which is pivoted at 89 to the frame of the machine. A second stud 90 is fixed to the lever 88 and is adapted to engage a lug 91 formed on the ratchet member 12. It is evident that as the cam surface 85 rotates in a clockwise direction, as seen in Figs. 8, 9 and 10, the stud 87 will gradually be lifted by the cam 85 and caused to move toward the platen shaft 13, thus raising the lever 88 and the second stud 90 carried by said lever, and causing said stud 90 to engage with the lug 91 formed on the ratchet member 12, thus rotating the ratchet in a clockwise direction, as viewed in Figs. 8, 9 and 10, and causing one or more of the ratchet teeth to ride over the pawl 53, thus setting the ratchet member.

Mechanism is provided to prevent the setting action of the lever 88 from being repeated after the ratchet member has been set, and also to prevent interference with the free action of the ratchet member when it is released for the purpose of causing the striker hammer to operate. This mechanism as shown may include an open space 96 in the cam surface 85, which is formed, as shown in Fig. 11, with a substantially radial surface 97, down which the stud 87 rides (see Figs. 9 and 10) to cause it to ride clear of the cam surface 85 after the ratchet member 12 has been set. A supplementary lever arm 98 is provided to turn on the pivot 89 and is urged by a spring 99 against a pin 100 fixed on the lever 88 so that the arm 98 and lever 88 ordinarily move together. A pin 101 is fixed in the free end of the arm 98 and is adapted at one stage of its operation to engage a short cam-shaped surface 102 formed on the ratchet member 12.

The complete action of the mechanism shown in Figs. 8 to 12 inclusive is as follows: In Fig. 8 the cam 85 is just engaging the stud 87. In Fig. 9 the stud 87 has been moved to its highest point by the rotation of the cam surface 85 caused by the rotation of the platen, and the ratchet member 12 has

thus, through the engagement of the pin 90 with the lug 91 on the ratchet, been brought to its set position. In Fig. 10 the stud 87 has been released after further rotation of the platen and the cam 84, and is clear of the cam surface 85 and occupies a position below the lowest point of travel of the cam. The supplementary lever arm 98 is urged against the pin 100 by the spring 99 and when the lever 88 has moved to its lowest position as shown in Fig. 10, the supplementary lever arm 98 prevents the stud 87 from falling to a lower point by the engagement of the stud 101 with the cam surface 102 on the ratchet member. When the ratchet member is released from the pawl 53, causing the hammer to strike the bell, this rotary movement of the ratchet member moves the cam surface 102 against the pin 101, lifting said lever 98 by means of said pin to the position shown in Fig. 8, thus bringing the lever 88 back to its initial position. If the ratchet member 12 should be released at a time when the cam 84 is in such a position that the stud 87 is not opposite to the open space 96, but is outside of and below the cam surface, thus preventing the cam 85 from raising the pin 87 and with it the lever 88, then the auxiliary lever arm 98 will be lifted by engagement of its stud 101 with the cam surface 102 on the ratchet member, thereby moving away from the pin 100 and by means of the spring 99 urging the stud 87 against the lower bottom peripheral surface of the cam 85, and in this way placing the lever 88 under spring tension. This causes the stud 87 to enter the opening 96 as soon as this opening comes opposite to the stud 87 in the course of the rotation of the cam 84. At this moment, urged by the spring 99, the stud 87 is returned to its original position shown in Fig. 8.

This mechanism therefore provides for the automatic operation of the margin indicating mechanism, in such a way that it is set without attention on the part of the operator of the machine, by the mere and ordinary routine of operating the machine.

It will be seen that, by the mechanism herein described, the invention provides a page end margin indicator which is simple in its mechanical construction; which provides for the free and unobstructed insertion of the paper into the machine, without causing any part or parts to bear on the paper while it is being inserted, thereby eliminating all danger of tearing or scoring or otherwise marking or defacing the paper; an indicator which can be readily set to indicate margins of different depth; and which may, if desired, be entirely automatically set and actuated by the normal and ordinary movements of standard typewriting machine parts.

It will be apparent that various changes and modifications may be made in the con-

struction described without departing from the invention as defined by the appended claims.

What is claimed is:

1. A page end margin indicator mechanism for a writing machine having a platen, including a signal, means including a detent variably positionable circumferentially about said platen controlled by a page in the machine on which it bears for operating said signal to indicate when the writing approaches a selected distance toward the page end, and means for setting said detent to cause it to bear on said page after it has been inserted in the machine. 70

2. In a writing machine provided with a rotatable platen, a page end margin indicator mechanism including a signal, means including a detent variably positionable circumferentially about said platen and cooperating therewith and controlled by a page in the machine on which it bears for operating said signal to indicate when the writing approaches a predetermined distance toward the page end, and means for setting 75 said detent to cause it to bear on said page after it has been inserted in the machine, said setting means being associated with and automatically operated by standard operating mechanism in said machine. 80

3. A page end margin indicator mechanism for writing machines including a signal, variably positionable means including a detent controlled by a page in the machine for operating said signal to indicate when the writing approaches a predetermined distance toward the page end, means for variably positioning said detent to cause it to indicate a selected amount of margin, means associated with said signal operating means 100 normally urging said detent into a position to provide clearance for the insertion of a page into the machine, and means for setting said detent to cause it to bear on a page after it has been inserted in the machine, 105 said setting means being releasable by said detent to operate said signal, and, when released, permitting said urging means to move said detent into clearance position. 110

4. A page end margin indicator mechanism for writing machines, including a signal, variably positionable means including a detent controlled by a page in the machine for operating said signal to indicate when the writing approaches a predetermined distance toward the page end, means for varying the amount of margin to be indicated by variably and selectively positioning said detent, means associated with said signal operating means normally urging said detent into a position to provide clearance for the insertion of the page into the machine, and automatic means associated with and operated by standard operating mechanism in said machine for setting said detent to cause 115 120 125

it to bear on a page after it is inserted into the machine, said setting means being releasable by said detent to operate said signal, and, when released, permitting said urging means to move said detent into clearance position.

5. A page end margin indicator mechanism for writing machines including a signal, signal operating means including a ratchet member, variably positionable detent means controlled by a page in the machine and adapted to engage and hold said ratchet member and to release it at a predetermined moment, means for moving said detent means to any one of a plurality of positions, said setting means, upon being operated, automatically moving said detent means away from ratchet engaging position.

6. A page end margin indicator mechanism for writing machines including a signal, signal operating means including a ratchet member, variably positionable detent means controlled by a page in the machine and adapted to engage and hold said ratchet

member and to release it at a predetermined moment, lever means carrying said detent means for moving said detent means to any one of a plurality of positions, said lever means, upon being operated, automatically moving said detent means out of ratchet engaging position.

7. A page end margin indicator mechanism for writing machines including a signal, signal operating means including a ratchet member, variably positionable detent means controlled by a page in the machine and adapted to engage and hold said ratchet member and to release said ratchet member at a predetermined moment, lever means for moving said detent means to any one of a plurality of positions, locking means engaging said lever means and guiding said lever means to move said detent means out of ratchet engaging position while it is being set.

In testimony whereof I affix my signature.

NOEL DEISCH.
